UNITED STATES PATENT OFFICE.

ELIE W. LABOMBARDE, OF NASHUA, NEW HAMPSHIRE.

METHOD OF PACKAGING ICE CREAM.

Application filed September 11, 1924. Serial No. 737,081.

To all whom it may concern:

Be it known that I, ELIE W. LABOMBARDE, a citizen of the United States, and resident of Nashua, in the county of Hillsborough and 5 State of New Hampshire, have invented certain new and useful Improvements in Methods of Packaging Ice Cream, of which the following is a specification.

This invention relates to the production 10 of packages of commodities such as ice cream in measured quantities, and the object of the invention is to enable paper boxes to be quickly and accurately filled or loaded, which boxes will be leak-tight and of a more 15 economical type than those most commonly employed heretofore.

Paper or pasteboard boxes or pails most 20 commonly used at present, especially those which are filled in stores and carried home by individual customers, are of tapering shape so they may be nested for the purpose 25 of saving space when they are shipped or stored. Boxes of such shape can not be made otherwise than partly or wholly by hand or by very expensive machines which 30 are slow in production. And it is essential that boxes which are to be used for carrying ice cream from a store to one's home shall 35 have bottoms and side walls as leak-proof as possible. To attain the best results in 40 this respect, it has been necessary heretofore to make the boxes in open or set up condition with their bottom flaps adhesively secured. Therefore they could not be made 45 in flat folded condition and so shipped or stored. And this is true whether they are 50 of tapering form or are of uniform diameter from end to end, either square or cylindrical.

In carrying out my invention I preferably 55 employ paper boxes of the type illustrated and described in my application Serial No. 725,542, filed July 12, 1924, the blanks for 60 which are rendered moisture-proof and of 65 glossy appearance by a heavy coating of wax such as paraffine, said blanks being furnished to users in flat folded condition and 70 then set up by the users as wanted. Then, in further carrying out my invention, each 75 set up box is simultaneously filled and its bottom joints tightly closed by means of a 80 loader which, at a single operation, deposits just the amount of ice cream to fill the box 85 while acting on the bottom joints of the box 90

to prevent them from being forced open by 95 the pressure of said material.

Of the accompanying drawings:—

Figure 1 is a broken out perspective view 100 of the loader containing a mass of material such as ice cream.

Figure 2 is a broken out perspective view 105 of the loader discharging the material into a box.

Figure 3 sectional view illustrating the 110 action of the bottom edges of the walls of the loader on the bottom joints of the box.

To avoid confusion, reference numerals 115 are employed for the loader and reference letters for the box.

The loader has thin side walls 12 the bottom 120 edges of which are preferably bevelled as at 13 to facilitate entrance into the box. The tops of the walls 12 are connected by a bridge piece 14 to which is rigidly secured 125 a hollow stem or tube 15 having a vertical 130 slot 16 having a notch 17 the purpose of which will be presently explained. A handle 18 is secured to the upper end of the tube 15, and two finger pieces 19 are secured 140 to the opposite sides of said tube near the 145 bridge piece 14.

Mounted to slide in the tube 15 is a rod 20 having a finger piece 21 at its upper end 150 projecting through the slot 16 of the tube, the lower end of said rod extending through 155 a plate 22 and having a disk 23 at its lower end. Said disk 23 is illustrated in Figure 1 160 as of diamond shape for a purpose explained hereinafter. The plate 22 is of a size to just fit the transverse space inside the walls 165 12 to act as a plunger, while the connection between it and the plunger rod 20 permits 170 the latter to rotate when required for purposes presently explained.

The box which is preferably employed 175 is of the type illustrated in the application hereinbefore referred to, to which application reference may be had, if desired, for 180 its complete details. For present purposes it will be sufficient to explain that the box 185 comprises side walls *a* having foldable bottom flaps *b*, *c*, and *d*, the latter having a tucking flap *e* (Fig. 3), and foldable top flaps *f*, *f*, and *g*, the latter having a tucking 190 flap *h*. The flaps at both bottom and top 195 are substantially alike except that the *b*, *c*, which extend from opposite walls of the box 200 are long enough to extend in overlapping

condition entirely across the bottom of the box, while the similar flaps *f*, *f*, at the top are usually only long enough to enable their end edges to meet. The bottom tucking flap *e* extends past the side edges of the two long flaps *b*, *c*, and up against the inner face of one of the side walls *a*, as shown by Figure 3. It is this last mentioned joint at which leakage is most likely to occur.

The loader illustrated is supposed to be of one pint capacity, but the notch 17 enables it to be used for loading boxes of half-pint capacity as will be explained.

In operation, assuming that the box to be loaded is of pint capacity, the user grasps the handle 18 and pushes the loader into a mass of ice cream as far as it will go. The plunger plate 22 then automatically rises. Then upon lifting the loader from the mass, it will withdraw a quantity of ice cream which just fills the loader as indicated by Figure 1. The loader, with its contained material, is then quickly transferred to a box the bottom flaps of which have been closed as in Figure 3, said loader being pushed down as far as it will go. The box, of course, is to be supposed to be resting on a flat surface, so that the lower edges of the walls 12 of the loader will hold all bottom joints tightly closed. Then the user, with his or her fingers engaging the finger pieces 19, 21, as illustrated in Figure 2, forces the finger pieces toward each other, and this results in holding the plunger plate 22 stationary in the box while the walls of the loader are being drawn up and entirely out of the box. The action is such that while the lower edges of the walls of the loader ensure tight closing of the bottom joints at the beginning of the operation, the drawing up of said walls as described, while the plunger plate is holding the ice cream down, leaves the material packed tightly against said joints, leaving no air spaces.

Figure 2 illustrates the walls of the loader as partly withdrawn, leaving the ice cream well packed in the box, and it is to be understood that continued pressure of the finger pieces 19, 21, toward each other will finally effect complete withdrawal of said walls, leaving a solid mass of ice cream in the box, with the top marked or embossed by the design of the disk 23 on the under side of the plunger plate. The form of said disk may be other than diamond-shape, or may be anything to indicate the goods of the dealer employing the invention.

After the filling, and the withdrawal of the loader, the top flaps *f*, *g*, *h*, of the box

may be closed in a manner the same as employed when closing the bottom flaps prior to filling.

If the loader is to be employed for filling a box of half-pint capacity, the finger piece 21 of the plunger rod is, before pushing the loader into a mass of ice-cream, swung into notch 17 so that the plunger plate will occupy a position half way of the length of the walls 12. It is to enable this to be done that the connection between the rod 20 and the plunger plate 22 is so made that the rod can rotate as hereinbefore mentioned. To load a half-pint box with a half-pint of ice cream, the operation is the same as hereinbefore described except that before beginning to eject the ice cream from the loader, the finger piece 21 is first swung out of the notch 17.

My invention provides for furnishing accurately measured quantities of ice cream to customers, in leak-proof boxes which are sanitary, the filling of the boxes being effected in much less time than when employing a spoon or dipper as is now most commonly used. It enables boxes of low cost to be employed, and ensures complete, tight closures of the bottom flaps so as to avoid crevices. And the packing of the ice cream against the bottoms of the boxes ensures retention of the bottoms in condition to prevent exudation or leakage.

I am aware that many devices have been designed for lifting ice cream in measured quantities and discharging it into receptacles or onto dishes, but so far as I am aware none have been designed or proposed for use in the manner hereinbefore described.

Having now described my invention, I claim:

1. The method of producing a leak-tight package of plastic material contained in a paper box having interfolded bottom joints, consisting in mechanically holding the bottom joints of said box tightly closed, and while said joints are so held forcing the said material into said box and against the bottom thereof.

2. The method of packaging ice cream, consisting in first filling a loader with said material, then inserting the filled loader in a container having interfolded bottom portions, and then withdrawing the loader while holding the said material pressed against the bottom of the container.

In testimony whereof I have affixed my signature.

ELIE W. LABOMBARDE.
